[57] CLAIM

The ornamental design for a fishing lure body, substantially as shown and described.

DESCRIPTION

FIG. 1 is a perspective view of a fishing lure body embodying our new design.

FIG. 2 is a side elevational view of the design for fishing lure body of FIG. 1, the side not shown being a mirror image of the side shown.

FIG. 3 is a top plan view of the design for fishing lure body of FIG. 1, the bottom thereof being substantially identical thereto.

FIG. 4 is a front elevational view of the design for fishing lure body of FIG. 1.

FIG. 5 is a rear elevational view of the design for fishing lure body of FIG. 1.
